UNITED STATES PATENT OFFICE.

HARRY BRIDGMAN SMITH, OF BROOKLYN, NEW YORK, ASSIGNOR TO LIGHTSHIP CLOTH BOARD CORPORATION, OF BROOKLYN, NEW YORK, A CORPORATION OF NEW YORK.

METHOD OF MAKING CLOTH BOARDS AND SIMILAR ARTICLES.

Application filed April 1, 1922. Serial No. 548,626.

My invention relates to rapid, simple and economical methods of making cloth boards or similar articles.

The general object is to make a cloth board 5 of more or less hollow or cellular construction and of fibrous sheet material, which is very light, strong and sufficiently stiff, but at the same time to a substantial degree resilient or flexible, by improved and economical methods, and especially by what I call 10 a "continuous" method of production, so that the economy inherent in the article because of the nature of the material and the small amount of material required, is very much increased by the economy in the production 15 operations.

Briefly described, the invention comprises in one form the advancing of continuous strips or webs of fibrous sheet material, such 20 as paper or similar fibrous stock, of suitable qualities and thicknesses, producing upon certain of the webs indentations and projections, or more particularly stated, in a particular case ribbing or corrugating such 25 web or webs, bringing the web or webs so treated into contact with other flat webs, with adhesive properly applied between the contacting surfaces, to form an initial continuous assembly in which there is a center 30 or filler of the corrugated or similarly treated material with a substantially flat facing sheet on either side of it, longitudinally creasing or scoring the assembly to form folding lines, and folding over marginal 35 portions of the assembly along the folding lines, applying adhesive and pressing down these marginal portions upon the main or central part of the assembly with the edges 40 of said margins closely confronting or abutting each other, and then cutting the assembly transversely at regular intervals to produce individual cloth boards, the characteristics of which will be sufficiently described hereafter.

45 The invention also includes certain methods of "treating" some or all of the materials, and by "treating" is meant a method of processing the materials distinct and different from corrugating, shaping, bending 50 and cutting them. Such treating in the present invention consists in applying to or impregnating some or all of the fibrous sheet material with a hardening, stiffening or strengthening agent or material for the purpose of improving the structural qualities

of the stock in addition to its ordinary qualities, dependent merely upon the nature of its fibrous composition. As an example of such treatment, one or more sheets of the material is treated with a suitable liquid, such as a solution of sodium silicate, or a suitable "glue size", and this may be done by brushing the solution on one or both surfaces of the sheet or web, or by passing the web through the solution, or in other ways. 60 When properly dried, the solid component of the solution remains on or in the fibrous sheet and materially hardens, stiffens or strengthens it and adds to its structural value, so that, for example, a sheet of filler 70 material may be of especially low grade or cheap stock and by the described treatment is strengthened sufficiently for the purpose in view; or where the stock is of a better grade or quality, the treatment still further 75 increases its strength, stiffness or resiliency.

As a variation in the general production method previously described, the materials may be preliminarily partly formed or treated or partly assembled. For example, one 80 available material is what is called in the trade single faced corrugated board consisting of a sheet of corrugated paper or like material adhesively secured to a flat facing sheet. This single faced board may be provided in the form of a roll, and the material may be advanced continuously from the roll. Another facing sheet may be adhesively applied or secured to the corrugated, or unfaced, surface of the single faced board, the 85 initial assembly being thus completed, and thereafter the assembly may be treated as before.

Many other variations may be made within the principles of the invention, as sufficiently explained in connection with the following detail description of the accompanying drawings, which show in a more or less diagrammatic way certain representative performances of the method; and I contemplate any methods or method steps that are properly within the scope of the appended claims.

In the drawings:—

Fig. 1 is a diagrammatic view, partly in elevation and partly in section, showing one performance of the method.

Fig. 2 is a perspective view of the materials from the point of complete initial assembly to the point where the formation of 110

the continuous assembly is entirely completed.

Fig. 3 is a section on 3—3, Fig. 1.

Fig. 4 is a section on 4—4, Fig. 1.

5 Fig. 5 is a perspective view of a completed cloth board.

In one performance of the process, suitable sheet material, usually fibrous material, such as paper, cardboard, or the like, 10 is provided in the form of rolls 1, 2 and 3. The materials in the different rolls may be varied to suit conditions, but in one particular case the sheet material in roll 1 may be of relatively cheap fibrous stock, such as the 15 grade of stock usually known as "straw board", since this, when treated in accordance with my invention, is especially cheap and is sufficiently strong for many kinds of cloth boards. The material in the other rolls 2 and 3 may be of higher grade or 20 quality or greater thickness. In one particular example this material may be what is commercially known as "sulphite board" of moderate thickness, which is sufficiently 25 stiff and strong for the purpose in view, and at the same time is sufficiently cheap so that in combination with the other material and treated in accordance with my invention, an exceedingly cheap product is obtained.

The sheet of material 4 from roll 1 is passed between corrugating rolls 5 which have interfitting longitudinal surface ribs 6, the material being previously moistened 30 whenever necessary to provide for proper corrugation according to known methods. This step is an example of various ways of treating the core or filler stock to produce in it elevations and depressions, ribs or corrugations, or any other equivalent formation which provides the necessary structural 40 strength when associated with the other materials. The sheet or web 7 passing away from the rolls 5 is therefore, in the present 45 particular example, a continuous strip of corrugated straw board produced from the stock in the roll 1.

The cardboard or sulphite board is advanced in the form of a strip 8 from the roll 50 2, and passes over a glue roll 9, by which the under surface of the sheet is adhesively conditioned. A strip or web 10 of similar material is advanced from the roll 3 over a glue roll 11, by which the surface of the 55 web which is undermost at that point is similarly glued or adhesively conditioned.

All of the webs are then passed between cooperating pressing rolls 12 and 13 with corrugated sheet 7 between the flat facing sheets, this producing the initial assembly, or initiating the continuous assembly, consisting of the corrugated sheet in adhesive contact with the flat facing sheets. The assembly is advanced by any suitable means, for instance at a point beyond the rolls 12

and 13, it passes between other feed and pressing rolls 14 and 15, all of these rolls being suitably driven in any desired manner. The distance that the assembly travels after initial contact of the parts and before further operations are performed, depends upon the time required for the glue to properly set or harden, and to expedite hardening of the glue various means may be employed, for example in the zone 16 between the pairs of feed and pressing rolls the assembly may pass between hot plates or boxes 17 and 18, which may be heated in any suitable way, for instance by steam circulated through pipes 19 and 20, and by heating in this manner the glue is rapidly dried or set.

At a point beyond the rolls 14 and 15, the assembly is treated to facilitate bending along the lines 25, Fig. 2. In the present instance the assembly passes under an abutment roll 26, and below this round edge creasing rolls 27 are arranged on a shaft 28, and the rounded peripheries of these creasing rolls bend and press down the under facing layer 10 and the irregularities or corrugations of the filler 7, forming the longitudinal grooves, channels or bending lines 25. The upper surfacing layer 8 is substantially unaffected by this operation.

After the creasing, the creased surface of the assembly is adhesively conditioned by passing it over glue roll 30, and adjacent to this point the assembly also passes under a guide plate 32, and at a point beyond the glue roll the guide plate has downwardly and inwardly curved side portions 34, this guide plate with its side members sufficiently representing any suitable assembly bending or forming mechanism. By this means, the assembly margins 40 are first bent downward to the position shown in Fig. 4, and then folded up flat against the inner surface of the main or broad flat side 41 of the assembly, bringing the glued surfaces of the sheet 10 into engagement, and then the assembly is passed between pressing rolls 45 and firmly pressed.

The assembly is then cut at regular intervals along transverse lines 50, producing individual cloth boards B, Fig. 5, rotary cutting means being indicated in the form of rolls 55 provided with cutting blades 56. It will be understood, of course, that the particular devices employed may be varied greatly.

The completed article B, Fig. 5, is therefore produced from a continuous flat assembly consisting of facing sheets and an intermediate corrugated sheet (or its equivalent, as sufficiently explained above), with marginal portions of the assembly folded over and adhesively secured, and with the longitudinal edges 60 of these margins closely abutting. Folding is usually performed so that the edges, or at least the edge corners

65, are substantially rounded. The assembly is then cut and individual boards B are produced, which are very light and cheap because of the economy in the quality and 5 quantity of material and the rapid and inexpensive production method; they are also very strong and sufficiently stiff on account of the ample structural strength of the corrugated material reinforced by the surface- 10 ing and intermediate layers of flat material with most or all of the surfaces firmly secured together by adhesive, and they are also to a substantial degree resilient or flexible, and the edges are more or less compressible or "soft." Such a cloth board fully 15 complies with the requirements of the textile trade for bolt centers or fabric winders of this class.

In the preceding detail description, the 20 materials have been described as being used practically in their natural state, that is, the various sheet fibrous materials are not processed or "treated" except for the various gluing, drying, shaping or bending, 25 pressing and cutting operations. In some cases, however, it is desired to additionally process or treat the materials, some or all of them. Fig. 1 shows such a treatment method applied only to the filler sheet or web 30, at a point between its removal from the roll 1 and its corrugation by rolls 5. A suitable hardening, strengthening or stiffening material, such as in a particular example a 35 solution of sodium silicate, is applied to the web or sheet after it leaves the roll, and this solution may entirely impregnate the sheet, or may be more or less in the nature of a surface coating. After application, it 40 is entirely or sufficiently dried before the corrugating operation, or in some cases the material may be treated after corrugating.

When the strengthening material is mainly in the nature of a surface coating, it may 45 be brushed or sprayed on, or otherwise suitably applied. When it is intended to impregnate the sheet material, however, the sheet may be submerged in the solution. As 50 an example of the last-named mode of application, Fig. 1 shows the web passing down into a tank 70 under a roller 71, so that the web is immersed in the solution 72 of sodium silicate, and thereafter it is sufficiently dried by passing over a series of rolls 73, one of which, as 74, may be heated 55 by steam or otherwise. Evidently, any of the other webs of material may be similarly treated when desired.

The structural characteristics of the completed article, (Fig. 5), are therefore in this 60 instance further improved, in addition to the natural strength of the fibrous material, by the hardening or strengthening agent, this being sufficiently indicated in the drawing by the legend applied to the filler material; and it will be understood that this may

also apply to the other materials when necessary or desirable.

In some cases this "treatment" may consist in applying a suitably strong or stiff glue or "glue size" to an entire surface of a 70 flat sheet which is thereafter brought into adhesive contact with the corrugated sheet, and in this way the adhesive engagement is secured, and at the same time the glue or size covering the entire flat sheet surface or surfaces materially stiffens and strengthens it 75 and the complete structure.

While I have above described a complete process of producing the articles from originally flat rolled material, the process 80 may commence with some of the materials in other forms. For instance, the corrugated sheet may be provided in association with a surfacing sheet, this being the well-known single faced corrugated board which can be 85 rolled and may therefore be advanced from a roll and associated with another surfacing sheet, such for example as the sheet 8, with adhesive properly supplied, and from that point on the process may be as previously 90 described. Or corrugated paper in rolls without any surfacing sheet may be furnished and advanced and associated with two surfacing sheets, and so on as above.

In one form of the invention also the 95 method may be understood to begin substantially at a point slightly anterior to the creasing rolls 27, or say at about the point represented by the left-hand edge of the assembly in Fig. 2; or in other words, in the 100 beginning of the method the materials may be already assembled in flat form and glued and the invention method then consists in creasing, bending, adhesively securing the 105 margins 40, and cutting off, as above described.

I claim:

1. A method of producing cloth boards or like articles, comprising advancing a continuous assembly including a flat surfacing sheet and a corrugated sheet adhesively connected, creasing the assembly to produce folding lines spaced inward from the edges, folding over and adhesively securing the outer portions of the assembly defined by the creases upon the flat central portion with the edges of said outer portions substantially abutting, and severing the assembly on transverse lines to produce the individual 110 boards.

2. A method of producing cloth boards or like articles, comprising advancing a continuous assembly including flat surfacing sheets and a corrugated core adhesively connected, creasing the assembly to produce folding lines spaced inward from the edges, folding over the outer portions of the assembly defined by the creases upon the flat central portion with the edges of said outer portions substantially abutting and securing 115 120 125 130

the parts in adhesive contact, and severing the assembly on transverse lines to produce the individual boards.

3. A method of producing cloth boards or like articles, comprising advancing a continuous assembly including flat surfacing sheets and an intermediate corrugated sheet with adhesive between engaging surfaces, applying heat to set the adhesive, creasing the assembly to produce folding lines, folding over and adhesively securing outer portions of the assembly to the central portion with edges of said outer portions substantially abutting, and severing the assembly transversely.

4. A method of producing cloth boards or like articles, comprising advancing a plurality of continuous flat sheets of fibrous material, corrugating one sheet and bringing the sheets in flat adhesive contact to produce a continuous assembly, creasing the assembly longitudinally, folding over the outer portions and adhesively securing them to the central assembly body with edges of said outer portions in substantially abutting relation, and severing the assembly transversely at regular intervals.

5. A method of producing cloth boards or

like articles, comprising advancing three continuous flat sheets of fibrous material, corrugating the intermediate sheet and bringing the sheets in flat adhesive contact to produce a continuous assembly, creasing the assembly, folding over the outer portions and adhesively securing them to the flat central assembly body with edges of said outer portions in abutting relation, and severing the assembly transversely at regular intervals.

6. A method of making cloth boards and the like, comprising advancing continuous sheets of flat fibrous material, treating certain of the sheet surfaces with adhesive, strengthening, sizing, corrugating an intermediate sheet and connecting it to flat surfacing sheets, creasing the assembly longitudinally and folding over the outer portions and adhesively securing them to the central portion of the assembly with edges of said outer portions substantially abutting, applying heat to set and harden the sizing, and severing the assembly on transverse lines to produce the individual cloth boards.

Signed at New York city, in the county of New York and State of New York, this 29th day of March. A. D. 1922.

HARRY BRIDGMAN SMITH.
